UNITED STATES PATENT OFFICE.

MASON V. CARTER, OF JEFFERSON, WISCONSIN.

VIGNETTER.

SPECIFICATION forming part of Letters Patent No. 745,324, dated December 1, 1908.

Application filed April 6, 1903. Serial No. 151,368. (No model.)

To all whom it may concern:

Be it known that I, MASON V. CARTER, a citizen of the United States, residing at Jefferson, in the county of Jefferson and State of Wisconsin, have invented a new and useful Vignetter, of which the following is a specification.

This invention relates to vignettters, and has for its object to provide a support for a vignetting-card by means of which the height and angle of inclination of the card may be adjusted by the photographer without leaving his station behind the camera.

A further object of the invention is to improve the construction and operation of vignettes, so that the adjustments thereof may be effected with less difficulty and in less time than in vignettters as heretofore constructed.

A further object of the invention is to simplify the construction of vignettters and to so form and arrange the parts as to present a neat and attractive appearance at all times and to be readily foldable, so as to occupy but little space when not in use.

With the object above stated and others in view, which will appear when the invention is more fully disclosed, the same consists, generally stated, in a supporting-arm pivotally connected with the forward end of a camera-stand, a card-holder mounted on the free end of said pivoted arm, and means operable by the photographer from his position behind the camera for raising and lowering said supporting-arm and adjusting the position of the card-holder thereon.

In describing the invention reference will be had to the accompanying drawings, forming a part of this specification, in which corresponding parts are designated by the same characters of reference throughout the various views in which they appear, it being understood that changes may be made in the form, proportions, and exact mode of assemblage of the elements exhibited without departing from the spirit of the invention or sacrificing and of its advantages.

In the drawings, Figure 1 is a view in perspective of a camera-stand with my improved vignetter attached thereto, the parts of the vignetter being disposed in operative position. Fig. 2 is a plan view of the vignetter and the top of a camera-stand. Fig. 3 is a side elevation of a camera-stand with the

vignetter in inoperative position. Figs. 4 and 5 are detail views showing the construction of the extensible adjusting-rod and the means for locking the operating-rods in position.

Referring to the drawings, 1 designates a camera-stand of ordinary type having attached thereto at the forward end, by means of screw-eyes 2 the main shaft 3 of the vignetter. The main shaft 3 has projecting in alinement with the median line of the camera-stand an arm 4, composed of telescopic members 5 and 6, which are adjustable in position by means of a clamping-collar 7 and which forms the main supporting-arm of the vignetter. The section 5 is rigidly secured to the main shaft 3 in any desired manner. Section 6 has at its forward end a rounded head 8, provided with a transversely-disposed opening 70 for the insertion of a pivot 9, upon which is mounted an arm 10, preferably formed of sheet metal and having a U-shaped cross-section, as shown. The arm 10 is provided at its upper end with a clip 11 for supporting a vignetting-card 12 of the usual type. As the arm 10 supports the clip 11, it will hereinafter be referred to as the "clip-arm" or "clip-supporting arm."

The main shaft 3 has inserted into one side 80 thereof a pair of screw-eyes 13, which afford journals for the crank-shaft 14, at each end of which there is a curved terminal lying in a plane substantially at right angles to the main portion of the crank-shaft. One of said terminals lies immediately adjacent to the arm 4, and the curvature thereof is directed forward. The other terminal of the crank-shaft is adjacent to the end of the main shaft 3 and is directed rearward. Pivotaly attached 85 to the first-named terminal is a connecting-rod 15, composed of two half-round members 16 and 17, connected by means of a clamping-collar 18. The member 16 has its end connected with one terminal of the crank-shaft 95 14 and is downwardly curved, as shown. The member 17 has its end connected with the clip-supporting arm 11 and is upwardly curved, as is also shown in the drawings. At the right end of main shaft 3, which is adjacent to one 100 end of the crank-shaft 14, there is rigidly mounted a curved arm 19, having substantially the same curvature as the adjacent terminal of crank-shaft 14. The curved arm

19 and the adjacent terminal of crank-shaft 14 are connected by means of curved links 20 and 21 with operating-rods 22 and 23, preferably of the form shown, each having at its forward end an upwardly-bent portion, designated 24 and 25 and terminating at the rear in eyes 26 and 27. The operating-rods 22 and 23 pass rearward through guide-loops 28 and 29, and in order to hold them in any desired position the operating-rods are provided on their under surfaces with notches 30, which are adapted to be brought into engagement by the resiliency of the material of which the rods are composed with a lug 31, formed by bending upward the rear end of the base of the guide 29.

The clip 11, in which the vignette-card 12 is supported, may be of any suitable construction, but the preferred form is that illustrated, and consists of a rod 32, having a central horizontal portion 33 and upturned ends 34, and the spring clamping member 35, the ends of which are coiled around the horizontal portion 32 of rod 31 and lock 25 against the upturned ends 33, thus causing the spring to engage normally with the upturned ends of the rod, as shown.

In use the lengths of supporting-arm 4 and connecting-rod 15 are adjusted by means of 30 the clamping-collars provided thereon to suit the focal length of the lens of the camera with which the vignette is used. The vignette-card 12 is mounted in the clip 11 in the usual way, and the device is set in position by means of the operating-rods 22 and 23. Rod 22 is connected with link 20, which is in turn connected with arm 19. Rod 23 is connected with link 21, which is pivotally connected with the terminal of crank-shaft 40 14, so that a pull upon the rod 22 will cause the elevation of the arm 4 and a pull upon rod 23 will turn the crank-shaft 14 in its bearings and through the connecting-rod 15 will swing the clip-supporting arm 10 toward 45 the camera. The notches on the under surface of each of the operating-rods are so formed that the rods may be drawn backward freely over the lug 31 without obstruction therefrom; but when the rods are released the notches will be engaged by the upturned lug on the base of guide member 29, thus preventing the rods from moving forward. In order to lower the vignette when it is desired to fold it and get it out of the 50 way, the rear ends of the operating-rods must be raised before they can be moved forward to lower the sections of the vignette. As it is desirable when the vignette is out of use to have the clip 11 held in as nearly vertical 55 position as possible to keep the card out of the way, the operating-rod 23, by means of which the position of the vignette is adjusted, will be normally held in retracted position, with the terminals of the crank-shaft 14 disposed upward, so that the vignette will be held in the position shown in Fig. 3.

As the ends of the operating-arms 22 and

23 lie near the rear portion of the camera-stand and as they alone form the means for controlling the movement of the vignette-card after the length of the supporting-arm 4 has been adjusted to the focal length of the camera-lens, it is clear that the photographer will not be obliged to leave his position behind the camera in order to adjust the vignette-card to the desired position, but the desired adjustment may be accomplished as well from the position behind the camera by means of the operating-rods as it could be done by hand if he were in front of the camera. Indeed, aside from the gain in time resulting from the photographer not having to leave his position behind the camera there is an additional gain, because the adjustments may be effected while the photographer 85 is watching the effect of the vignette as seen upon the ground glass of the camera and is thus enabled to tell at once when the desired adjustment is obtained. When a vignette is adjusted from the front of a camera, it is 90 necessary after making each approximate adjustment to return to the rear of the camera to observe just what the effect is, and consequently it is only after a succession of attempts to set the vignette in proper position 95 that it can be accomplished. By the device hereinbefore described it is possible to set the vignette in almost exactly proper position at the first attempt, as the height of the vignette-card is controlled by the lever, which 100 may be set very accurately at the first effort, and the inclination of the vignette-card, which will not materially affect the height of the upper edge thereof, is accomplished by another lever, so that only one lever need be 105 operated at a time and the photographer's attention may be directed solely to the effect of the vignette and not to the means of adjusting it.

Having thus described the construction and 110 operation of my invention, what I claim as new, and desire to secure by Letters Patent, is—

1. The combination in a vignette of a supporting-arm adapted to be pivotally connected with the forward end of a camera-stand and to hang normally downward, a clip-arm at the free end of said supporting-arm, and means operable from the rear of the camera-stand for raising and securing said supporting-arm in position.

2. The combination in a vignette of a supporting-arm adapted to be pivotally connected with the front end of a camera-stand and to hang normally downward, a clip-arm pivotally connected with the free end of said supporting-arm, operating means connected with said supporting-arm and operable from the rear of the camera-stand, and means also operable from the rear of a camera-stand for 120 folding said clip-arm against said supporting-arm.

3. The combination in a vignette, of a shaft, bearings for said shaft on the front of

the camera-stand, a supporting-arm rigidly secured to said shaft, a clip-arm pivotally mounted at the front end of said supporting-arm, a crank-shaft supported in bearings provided on the first-mentioned shaft, connections between said crank-shaft and said clip-arm, and separate operating means operable from the rear of the camera-stand for the shaft carrying the supporting-arm and the crank-shaft mounted thereon.

4. The combination in a vignetter of a shaft, a supporting-arm rigidly secured to said shaft, bearings for said shaft on the front end of a camera-stand, an arm rigidly attached to one end of said shaft, an operating-rod mounted in guides on said camera-stand, a link connecting said operating-rod and said arm, and means for engaging said operating-rod to hold said supporting-arm in any position.

5. The combination in a vignetter of a shaft pivotally mounted on the front end of a camera-stand, a supporting-arm rigidly attached to said shaft, a clip-arm pivotally connected with the free end of said supporting-arm, a crank-shaft mounted in bearings on said first-mentioned shaft, a connecting-rod attached at one end to a terminal of said crank-shaft and at the other end to said clip-arm, and devices operable from the rear of the camera-stand for adjusting the position of the first-mentioned shaft and adjusting the position of said crank-shaft.

6. The combination in a vignetter of a shaft pivotally attached to the front end of a camera-stand, an extensible supporting-arm

rigidly mounted on said shaft, a lever-arm secured also to said shaft, a crank-shaft pivotally mounted on said first-mentioned shaft, a clip-arm pivotally mounted on the free end of said supporting-arm, an extensible connection between said crank-shaft and said clip-arm, operating-rod for the first-mentioned shaft and the crank-shaft slidably mounted on the camera-stand, links connecting said operating-rod with a lever-arm on said first-mentioned shaft, and a terminal on the crank-shaft, and means provided on the camera-stand for engaging said operating-rod to hold them in any desired position.

7. The combination in a vignetter of a supporting-arm pivotally attached to the forward end of a camera-stand, a clip-arm pivotally attached to the free end of said supporting-arm, means for adjusting the position of said clip-arm on said supporting-arm, and means for raising and lowering the said supporting-arm comprising an operating-rod associated with said supporting-arm, guideways for said rod mounted on said camera-stand, a series of notches on the under surface of said rod, and a lug on said stand adapted to engage with said notches.

In testimony that I claim the foregoing as my own I have hereto affixed my signature in the presence of two witnesses.

MASON V. CARTER.
